US00D797430S

(12) **United States Design Patent** (10) **Patent No.:** **US D797,430 S**
Granger et al. (45) **Date of Patent:** **** Sep. 19, 2017**

(54) **SHOE INSOLE**(71) Applicant: **Spenco Medical Corporation**, Waco, TX (US)(72) Inventors: **David B. Granger**, Lorena, TX (US); **Jacob Martinez**, Temple, TX (US)(73) Assignee: **Implus Footcare, LLC**, Durham, NC (US)(**) Term: **15 Years**(21) Appl. No.: **29/533,221**(22) Filed: **Jul. 15, 2015**(51) LOC (10) Cl. **02-04**

(52) U.S. Cl.

USPC ..... **D2/961**(58) **Field of Classification Search**

(57) **CLAIM**

The ornamental design for a shoe insole, as shown and described.

DESCRIPTION

FIG. 1 is a perspective view of a shoe insole showing our new design;

FIG. 2 is a bottom view thereof;

FIG. 3 is a top view thereof;

FIG. 4 is a medial side view thereof;

FIG. 5 is a lateral side view thereof;

FIG. 6 is a front view thereof; and,

FIG. 7 is a back view thereof.

1 Claim, 5 Drawing Sheets
